ABSTRACT: A mechanism and method for uniformly spreading apart a group of dice formed from a unitary semiconductive wafer after the dice have been severed from each other but before they are otherwise spread comprising a stretchable diaphragm secured at its periphery by an annular frame with the diaphragm adapted to be stretched over a surface having a circular edge and with the diaphragm adapted to be secured in its stretched position by engagement with the edge of a cylinder which fits over and is secured about the stretched diaphragm and surface.

METHOD OF SEPARATING DICE FORMED FROM A WAFER

BACKGROUND OF THE INVENTION

This invention relates to a means and method of spreading apart a group of spreadable objects comprising, for example, a plurality of dice immediately after being formed from a single semiconductive wafer.

In a variety of arts it is desirable to provide a simple and efficient means for uniformly spreading a group of components which are closely spaced in their original position. There is a particular need for such a method and device in the semiconductor art where thousands of minute pinhead-sized dice are simultaneously formed from a single wafer of semiconductive material. After formation of these multitude of dice they must be severed from each other and separately removed for subsequent insertion in individual semiconductor devices. While it is possible to separate these dice manually, or by other means, the methods practiced heretofore have not been satisfactory for a variety of reasons. In order to maximize the efficiency of handling these severed dice it is most desirable to physically spread them apart while still maintaining the relative orientation of the dice one to the other. Manual separation and other means for effecting such a controlled spreading or separation has not been satisfactory, and as a consequence present methods of separation are quite expensive and time consuming. In addition it is desirable to minimize the physical handling by humans or machinery of the dice since they are fragile and susceptible to damage in handling.

SUMMARY OF THE INVENTION

It is therefore an object of the present invention to provide an improved means and method of spreading apart minute objects while still maintaining them in a selected orientation relative to each other. A further object of this invention is to provide an efficient means and method of spreading semiconductive components, especially dice, once they have been separated from a semiconductive wafer, with little damage or loss of individual components.

A further object of the present invention is to provide a relatively inexpensive mechanism which is easy to manufacture, maintain, repair and use for spreading small components.

In the present invention there is provided a mechanism for spreading apart a plurality of discreet objects comprising a resilient stretchable diaphragm designed to support the objects. Means are provided at the periphery of the diaphragm to support it for stretching over a surface having a periphery smaller than the periphery of the diaphragm and over which the diaphragm may be stretched in a plurality of directions preferably including directions normal to one another whereby objects on the diaphragm may be spread apart as the diaphragm is stretched, with the objects spreading uniformly in radial directions from a common center.

These and other objects and advantages of the present invention will be more clearly understood when considered in conjunction with the accompanying drawings.

BRIEF DESCRIPTION OF THE DRAWINGS

In the drawings FIG. 1 is a partially cross-sectioned elevational view of a device embodying the mechanism of the present invention, FIG. 2 is a partially cross-sectioned top plan view of the embodiment illustrated in FIG. 1, and FIG. 3 is a somewhat schematic plan view of discreet components of the type which are to be spread.

DESCRIPTION OF THE PREFERRED EMBODIMENT

In the drawings there is illustrated a preferred embodiment of a mechanism designed to uniformly spread discreet components. The particular embodiment illustrated is specially designed for spreading dice cut from a common semiconductive wafer. Ordinarily extremely thin semiconductor wafers having a diameter of 1 inch to several inches in magnitude are

scribed into hundreds to thousands of relatively small dice, in the order of magnitude of pinhead size. These dice are cut apart by conventional techniques. When the dice are separated they usually are scribed then broken or ordinarily remain in place relative to one another. It is then necessary to separate or spread them so that the operator can individually pick them up and put them into the header of a semiconductor device being formed or alternatively otherwise treat them.

In the drawings there is provided a diaphragm 1 of any suitable stretchable material such as rubber or synthetic material which is capable of stretching and then returning substantially to its original shape. This diaphragm is preferably secured by an annular band means 20 which in turn is preferably composed of an inner band 21 and an outer band 22. The diaphragm is secured in such a fashion that it is relatively planar and nonstretched or only slightly stretched when secured by the band means 20 and not under tension. The diameter of the band means is greater than the diameter of the platform 5 which has an upper surface 6 with a circular periphery 7. The platform 5 is suitably supported by a post 8 on a base 9 which may be rectangular or triangular in shape and which should have sufficient mass to adequately support the platform 5 and the other components herein described. A plurality, preferably three, support posts 15 extend upwardly parallel to the post 8 with distances spaced from the post such as to permit the annular band 20 to be moved downwardly between the three posts 15. These posts 15 extend upwardly preferably above the level of the surface of the platform 5. The posts 15 have a clamp mechanism 16 supported thereon and secured at a desired position by a setscrew 17.

The post is also provided with a tab 19 adapted to be rotated about the post with the tab secured against axial movement by a bushing and screw mechanism 25 and 26 which holds the tab 35 against the clamp 16. The tabs 19 have lips or ends such as to permit them to engage the flange 12 of the cylinder 10 after the flange has been pushed downwardly below the level of the tab.

The cylinder 12 is preferably formed of a transparent plastic material and is provided with a cylindrical outer wall 28 having a removable cover 13 and an outwardly extending flange 12 about its periphery with the flange 12 intermediate its upper end 29 and lower end 11. The flange 12 has sufficient width to permit engagement with tabs 19 when the tabs are rotated from an outwardly extending position to one directed inwardly towards the surface 6.

In the present invention after the semiconductor wafer is scribed by conventional means to define a plurality of dice in the then still integral wafer it is placed in this integral form scribed side down on a relatively soft surface, as for example a filter paper. The wafer then is rolled with a small hard roller in a conventional fashion to break the wafer into a plurality of dice along the scribe lines. Following this the dice, after being broken apart, are picked up while still in their same relative nonspread position one to the other by the device shown in FIG. 1. The dice are picked up by turning the unit over so that the diaphragm 1 in its undistended or unstretched position is pressed against the obverse side of the dice which have been

50 scribed and broken with their upper or treated surface face downwardly on the soft rubber surface. The diaphragm is then turned right side up with the dice clinging to the surface of diaphragm 1 so that their reverse surfaces or faces are visible. The diaphragm is then lowered downwardly over the surface 6 of the platform 5 whereby the diaphragm 1 is stretched uniformly in all radial directions from the center axis of the platform 5 thereby uniformly spreading the dice a distance which may be varied depending upon the desired degree of stretch, but is exemplified, for example, by the space 50. The 55 diaphragm may be stretched by lowering the cylinder 10 downwardly so that its lower edges 11 uniformly engage the upper surface of the diaphragm outwardly of and equally distant from the periphery 7 of the surface 6. The cylinder 10 may be secured in a desired position by interengaging the 60 clamp means 20 with the outwardly extending peripheral 75

flange 12 of the cylinder thereby securing the dice 70 in their desired spread relation with respect to one another. The cover 13 of the cylinder 10 may then be removed. Following this a flat hard support plate not shown, which has been wet may be pressed downwardly onto the dice to remove them in this spread position illustrated in FIG. 1 for further treatment.

We claim:

1. A method of separating dice formed from a wafer of semiconductive material after said dice have been separated

but are immediately adjacent one another in their original relative wafer orientation comprising: transferring said separated dice in said original orientation to a stretchable diaphragm face down; stretching said diaphragm in a plurality of directions whereby said dice are moved apart; and thereafter removing said dice from said diaphragm simultaneously after separation by pressing a wet plate against said dice with said face remote from said plate.
